UNITED STATES PATENT OFFICE.

JOSEPH LUCCINO, OF NEW YORK, N. Y.

CONVERTIBLE AND FOLDING COUCH AND CHAIR.

1,145,777.

Specification of Letters Patent.

Patented July 6, 1915.

Application filed January 16, 1914. Serial No. 812,449.

To all whom it may concern:

Be it known that I, JOSEPH LUCCINO, a citizen of the United States, and a resident of the city of New York, borough of Brooklyn, in the county of Kings and State of New York, have invented a new and Improved Convertible and Folding Couch and Chair, of which the following is a full, clear, and exact description.

10 The object of the invention is to provide a new and improved convertible and folding couch and chair arranged to permit of conveniently converting the couch into a chair or vice versa, or folding the same to form a 15 comparatively small bundle for ready storing or transporting purposes.

In order to accomplish the desired result use is made of a head section, a middle or a chair section and a foot section, the sections 20 being pivotally connected with each other and when extended form a couch or bed, the head section being adapted to be swung upward to form a back for the middle or seat section, and the foot section being adapted 25 to fold onto the middle section to form with the said head and middle sections a chair. Use is also made of legs for supporting the head section, the leg being connected by a link with the adjacent leg of the middle 30 section, and a retaining device held on the said adjacent leg to engage the said link with a view to hold the head section in upright position.

A practical embodiment of the invention 35 is represented in the accompanying drawings forming a part of this specification, in which similar characters of reference indicate corresponding parts in all the views.

Figure 1 is a plan view of the convertible 40 and folding couch and chair with the sections extended to form a couch, part of the head section being broken out; Fig. 2 is a side elevation of the same; Fig. 3 is a similar view of the same with the sections extended to form a chair; Fig. 4 is a front end view of the same; Fig. 5 is a side elevation of the same with the sections in folded position and Fig. 6 is a plan view of part of the chair.

50 The convertible and folding couch and chair consists essentially of a head section A, a middle or chair seat section B and a foot section C, of which the latter is connected by hinges C' to the lower end of the middle section B while the upper end of the latter is pivotally connected with a hori-

zontal extension D' of a leg D, on which the lower end of the head section is pivoted so that the sections A, B and C can be folded one relatively to the other, as hereinafter 60 more fully described. The forward or upper end of the head section A is provided with a pivoted leg E pivotally connected at each side by links F with the lower end of the leg D, and each link F is provided with 65 a pin F' adapted to be engaged by one of a series of notches G' formed in a retaining lever G fulcrumed on the leg D and pressed on by a spring G². The retaining lever G serves to lock the head section A in upright 70 position, as shown in Figs. 3 and 4, at the time the said head section forms the back for the chair, the seat of which is provided by the sections B and C, of which the latter is folded upon the section B.

The lower end of the middle section B is provided with a pivoted leg H connected at each side of the body by links I with the leg D, preferably at the same pivot connecting the link F with the said leg. The leg 80 H is normally held in vertical position by braces J fulcrumed on the sides of the middle section B and having notches at their free ends engaging pins J' projecting from the sides of the leg H. Thus when the 85 braces J engage the pins J' the leg H is held locked in vertical position, but when the links J are disconnected from the pins J' then the said legs H can fold upon the under side of the section B, as indicated in Fig. 5. 90

The lower end of the foot section C is provided with a leg K pivotally connected at K' to the sides of the foot section C, and the said leg K is provided with upward extensions K² pivotally connected by links L with 95 pivots N held on the lower end of the middle section B and which pivots N also form the pivots for the leg H.

When the foot section C is swung from its extended position, as shown in Fig. 2, upwardly and over onto the middle section B then the links C impart a swinging motion to the leg K so that the said leg folds on the sides of the foot section C, as plainly indicated in Fig. 3, see also Fig. 5. The head section A is provided near its pivotal end with a cross bar A', preferably bent so as not to interfere with the bed spring or canvas cover, as the case may be. When the several sections are in extended position, as 100 shown in Figs. 1 and 2, they form a bed or a couch, and when it is desired to convert this 105

2 couch into a chair then the operator swings the head section A upward and in doing so the pin F' engages one of the notches G' at the ends of the retaining lever G thus locking the head section A in the upright position into which it is moved by the operator. It will be noticed that when the head section A is in this upright position, as shown in Figs. 3 and 4, it forms the back of a chair. 10 The foot section C is swung upward and over onto the middle section B and in doing so the leg K is folded onto the sides of the foot section C and the middle section B now forms the seat of the chair together with the foot section C. When it is desired to fold the several sections into a small bundle for storing or transporting purposes then the operator disconnects the links J from the pins J' and disengages the retaining lever G from the pins F' to permit of swinging the leg A and link F closely onto the head section A and the leg D. It will also be noticed that after the braces J are disconnected from the pins J' the section B with the section C resting thereon will be swung upward, and in doing so the leg H is folded owing to the action of the link I so that the several folded parts take up very little room, as will be readily understood by 20 reference to Fig. 5. It will further be noticed that by pivoting the middle section B on the horizontal extension D' of the leg D sufficient room is had between the head section A and the middle section B to accommodate the foot section C between the same as shown in Fig. 3.

Having thus described my invention, I claim as new and desire to secure by Letters Patent:

40 1. In combination a head section and a chair seat section, the sections being pivotally connected with each other and the said chair seat section having pivoted legs at each end and the said head section having pivoted legs, links connecting the legs of the head section with the adjacent legs of the chair seat section, a pin on said link, and a

notched retaining lever adapted to engage the pin on the link for the leg of the said head section, the said lever being fulcrumed 50 on the adjacent leg of the chair seat section.

2. In combination, a chair seat section having legs, a head section pivotally connected with the said chair seat section and having pivoted legs, a link pivotally connecting the lower ends of the said head section legs with the lower ends of the adjacent legs of the said chair seat section and a locking device comprising a yoke lever having notched end extensions, and held on the said 60 adjacent legs of the seat section, and engaging the links for the leg of the head section.

3. In combination, a chair seat section having legs, a head section pivotally connected with the said chair seat section and 65 having a pivoted leg, a link pivotally connecting the said head section leg with the adjacent leg of the said chair seat section, a retaining device held on the said adjacent leg and engaging the said link for the leg 70 of the head section, the said retaining device having a yoke lever having end extensions provided with notches, and a pin on the leg link adapted to be engaged by one of the said notches and a spring for holding 75 said retaining device locked.

4. In combination, a chair seat section having legs pivoted thereto, a head section pivotally connected with the said chair seat section and having pivoted legs, a link pivotally connecting the said head section legs with the adjacent legs of the said chair seat section, a retaining device having a spring controlled lever provided with notches at or near its end, and a pin on the leg link of the 80 head section adapted to be engaged by one of said notches.

In testimony whereof I have signed my name to this specification in the presence of two subscribing witnesses.

JOSEPH LUPPINO.
